Primary Examiner — Derrick Holland*Assistant Examiner* — Lauren Calve(74) *Attorney, Agent, or Firm* — QuickPatents, LLC;
Kevin Prince(57) **CLAIM**

I claim the ornamental design for a hand grip, as shown and described.

DESCRIPTION

FIG. 1 is a perspective view of a hand grip according to a first embodiment;

FIG. 2 is a right-side elevational view of FIG. 1;

FIG. 3 is a left-side elevational view of FIG. 1;

FIG. 4 is a top plan view of FIG. 1, the bottom plan view being a mirror image thereof;

FIG. 5 is a front elevational view of FIG. 1;

FIG. 6 is a rear elevational view of FIG. 1;

FIG. 7 is a perspective view of a hand grip according to a second embodiment;

FIG. 8 is a right-side elevational view of FIG. 7;

FIG. 9 is a left-side elevational view of FIG. 7;

FIG. 10 is a top plan view of FIG. 7, the bottom plan view being a mirror image thereof;

FIG. 11 is a front elevational view of FIG. 7; and,

FIG. 12 is a rear elevational view of FIG. 7.
